[57] CLAIM

The ornamental design for a bobeche, as shown and described.

DESCRIPTION

FIG. 1 is a perspective view of a bobeche showing my new design;

FIG. 2 is a side elevational view thereof, the opposite side being a mirror image;

FIG. 3 is a bottom plan view thereof;

FIG. 4 is a cross-sectional view thereof as taken along 4—4 of FIG. 3.

The bobeche is transparent; however all elements which would normally appear through the side of the bobeche in FIG. 1 are omitted for ease of illustration and clarity of disclosure.
